UNITED STATES PATENT OFFICE

SIMON ROTHauszky AND JOHN SCHLER, OF AKRON, OHIO

ADJUSTABLE SECTIONAL BED

Application filed June 17, 1925. Serial No. 37,663.

This invention relates to beds and has for its main object to provide a bed made up of sections so that its head and feet portions, as well as its right and left sides, may be raised 5 from or lowered to a horizontal position and in general adjusted at the will of the user so as to give him or her the greatest possible comfort.

Another object of this invention is to provide a bed of the characteristics mentioned hereinbefore, the raising and lowering of the different portions of which will be executed by mechanical means in an automatic manner.

Still another object of this invention is to provide electrically operated mechanical means for adjusting the bed as mentioned hereinbefore which means may be conveniently and easily put in operation by a person while using the bed.

Other objects of the invention are: To provide an automatic adjustable bed which is simple in construction, easy to assemble, positive and smooth in operation and comparatively inexpensive to manufacture.

We long felt that a bed of the above characteristics would be a great benefit to sick and invalid people in hospitals, sanitariums, or even in homes, being laid up in bed practically in a helpless state and who have to rely on nurses or other outside help to adjust their beds to their greatest comfort. Our present invention solves this problem and fills the want, since a person lying in a bed constructed according to our invention may adjust the head or feet, the right or left hand side of his or her bed without any special effort, by simply pushing a button and keeping his or her finger on said button as long as he or she desires the bed to continue the adjusting movement selected. It is obvious that our invention is of great benefit also to other persons than the sick or invalid who want special comfort in their beds, and that the principles 45 of our invention may be applied to other

forms of furniture besides the beds, like to couches, sofas, etc.

With these objects, and such other objects as may herein appear, in view, the invention consists in the construction, arrangement and combination of the parts which will be herein-after fully described and afterward specifically claimed.

In order that its construction and operation may be readily comprehended. We will now proceed with a full, clear and specific description of the invention, having reference to the accompanying drawings, which show an approved, embodiment thereof, and in which—

Fig. 1 is a perspective view of a bed frame with the mattresses thereon constructed in sections according to our invention.

Fig. 2, is a perspective view of the base portion of the bed and its associated parts.

Fig. 3, is a central longitudinal sectional elevation of the bed all parts being in the normal position.

Fig. 4, is a partial cross sectional elevation of the bed about on the central line.

Fig. 5, is a detail cross sectional elevation through the bed frame and mattress with a section of the bed tilted.

Fig. 6, is a perspective view of the elements for actuating the bed sections.

Fig. 7, is a longitudinal sectional elevation of the electric power motor employed.

Fig. 8, is a perspective detail of the switch box employed in the selective bed section movements, and Fig. 9 is a diagram of the electrical connections employed in our invention.

Similar characters of reference refer to similar parts throughout the several views.

Referring now in detail to the drawings, the numeral 10 indicates a bed which for the purpose of our invention is made up of sections resting on a frame 11, also constructed of sections corresponding to the sections of the mattresses, as shown in Fig. 1. The springs and

other stationary elements of the bed are also made up of corresponding sections and this under structure will be covered by the usual bedding, which, being of a flexible nature, it will be obvious that the different sections of the bed may be moved, raised or lowered independently of the rest of the bed, as will be more fully explained hereinafter.

Hinges, like 12^a, 12^b, 12^c, 12^d, etc., are provided to join the different sections of the bed to one another and to permit their free movement with relation to each other. If we suppose that the end of the bed marked with the numeral 13 is the head of the same, and the end marked 14 represents the foot of the bed, then the sections 13^a, 13^b, and 13^c are the head sections and the sections 14^a, 14^b and 14^c are the foot sections, while the sections 13^a and 14^a together with the middle section 16 are the right side sections of the bed, and in a similar manner, the sections 13^c, 14^c and 15 are the left side sections of the bed. The section 17 in the center of the bed is stationary and will be permanently fixed to the supporting frame of our bed.

The bed is resting on a supporting or base frame 18, the center portion 17 being permanently fixed to the center member 19 of the base frame, while the other portions of the bed structure rest in horizontal position upon the upper ends of the four arms 20, 21, 22 and 23 to limit the downward movement of the different sections from raised position. Such members and elements may be easily constructed according to the usual methods employed in the art, and the limiting means for the downward movement of the different sections may also be incorporated in the respective hinges 12^a, 12^b, etc. as well known in the art.

Since the bed portion 15, 16, 13^b and 14^b are directly actuated for raising a part of the bed by means hereinafter described, and the corner portions of the bed, namely, 13^a, 13^c, 14^a and 14^c must move about transverse or longitudinal axis of the bed, as may be necessary to raise an end or side of the bed, coacting means 117 are provided to move the said corner portions from the central end and side portions. It may here be noted that the head portions 110 of the bed may be secured to the central end portions 13^b and 14^b in any suitable manner.

The adjustment and regulation of our bed is executed by raising or lowering the three head sections, or the three foot sections, as well as the three right hand sections or the three left hand sections, according to the desire and comfort of the user of the bed. Arm 20 of the base frame and the mechanisms cooperating with said arm, as will be more fully described hereinafter, serves to raise or lower the head sections of the bed, while in a similar manner, the arms 21, 22, and 23 serve to raise the left side, the foot, and the right side of the bed.

An electro-motor 24 is preferably arranged on the base frame to provide the necessary power for raising or lowering the different sections of the bed and a switch box 25, secured to an underside of the bed controls of operation of the electro-motor and the mechanisms connected therewith, the eight buttons shown on the switch box 25 serving for raising or lowering the four sections of the bed.

The inside mechanism of the base frame is shown in a semi-diagrammatical manner in Fig. 6. The electro-motor 24 carries a driving gear 26 at the one end of its shaft 27. Gear 26 is adapted to drive either the gear 28 used for the right side and left side movements of the bed sections, or to drive the gear 29 used for the head or foot movements of the bed sections. Said two gears are preferably placed in planes above and below the center driving gear 26, (Fig. 7), and also in different planes horizontally, the plane of the gear 28 being in front and the plane of the gear 29 in the back of the plane of gear 26, when said gear is in its normal position. Gear 26, therefore, normally is not connected, and in order to move the right or left sides of the bed, gear 26 must be moved forwardly, to the right side of Fig. 7, so as to engage the gear 28, and, vice-versa, the gear 26 will have to be moved in a left handed direction, as shown in Fig. 7, when it is our purpose to make the gear 26 act on the head or foot sections of the bed.

A semi-circular toothed segment 30 is housed in the hollow arms 20 and 22, slidably arranged therein, its end 31 adapted to catch and raise the head sections of the bed by any suitable means (not shown), when said end 31 is raised, or to permit said sections to be lowered smoothly and slowly when said end 31 is caused to recede. The opposite end 32 of the segment 30 will coact in a similar but reversed manner with the foot sections of the bed. The driving of the segment 30 is executed through the worm 33 journaled in the base frame and driven from the gear 29 through the intermediacy of shaft 34 and bevel gears 35 and 36. The sliding movement of the segment 30 in the arms 20 and 22 and in the base frame is facilitated by rollers 37 arranged at appropriate places in said arms and in the base frame. In a similar manner as has been detailed in connection with the toothed segments 30, the toothed segments 38 will be used to raise or lower the right hand or left hand side sections of the bed, the end 39 of the segment 38 being used for the raising or lowering of the right hand side of the bed, while the other end 40 of said segment may be used for the raising or lowering of the left hand side sections of the bed. Motion may be imparted to the segment 38, slidably housed in the hollow arms 21 and 23 and in the baseframe, by the gear 28, through the

intermediacy of the shaft 41, worm 42, and the teeth 43 on said segment. Rollers 44 facilitate the movement of the segment and take up most of the force and reactions acting thereon, while the downward pressure or weight carried by both segments will be taken up by the worms themselves, the shafts of which are safely and securely housed in the base frame.

10 The switch box 25 is arranged at any suitable place on the bed frame near the head portion of the same so as to be within reach of the sick or invalid person using the bed, and its buttons 45, 46, 47, and 48 will start 15 an upward movement of the head, feet, left side, and right side sections of the bed, respectively, while the buttons 49, 50, 51, and 52 control the downward movement of the same sections. Electrical connections, to be 20 described presently, are provided whereby the pressing of any one button will start such a movement of the bed for which said button is intended and will automatically prevent a simultaneous and confusing movement of any other portion of the bed. Triple 25 electrical contact springs 53 are provided with each button (Fig. 9), the said triple contact springs connecting with appropriate branches of the electrical circuits of our device through the binding posts 54, and are also secured together through insulating members 55 so that they execute simultaneous movements and either make or break the current in their respective circuits at the 30 same time. A pressure on any of the buttons 45 to 52 will cause the respective three spring contacts to close their circuits which will remain closed and the electricity will flow through the same as long as the button 35 is kept pressed, while upon the release of the button the spring contacts will automatically break the respective circuits.

The electro-motor 24 (Fig. 7) is not mounted on the shaft 27 directly but it is secured on a sleeve or tube 56 which carries a key 57 secured to the inside of the same and adapted to run in the key way 58 when the shaft 27 is moving to the right or to the left and drive said shaft in any position as soon 50 as the armature is caused to rotate. The motor may be of any standard type and is shown in the drawing with the armature 59, rectifier 60, and magnetic coils 61, within the housing 62. At the one end of said housing and adjoining the same in the solenoid case 63, containing the two solenoids 64 and 65, which provide the means to pull the shaft 27 into a right handed or left handed direction and cause it to engage the gears 28 or 29, according 60 to which solenoid will receive electrical energy. In order to enable the two solenoids to act on the shaft 27, said shaft is made of brass or other non-magnetic metal, having a soft iron ring 66 secured thereon between 65 the two solenoids. The forked member 67,

pivoted at 68, engages the ring 66, and has two side arms 68 and 69 cooperating with the spring actuated two slidable pins 70 and 71, indicated as springs 70, 71, in the diagram Fig. 9, which will tend to return the forked member 67, and through the action of the same the shaft 27, into its middle position, as shown in the Fig. 7, in which position the gear 26 is out of engagement with either of the bed operating gears 28 or 29. Should one of the buttons mentioned hereinbefore and closing one of the circuits necessary to operate the bed in the desired selected manner, be pressed, the motor 24 will receive 75 electrical energy and starts to rotate while at the same time one or the other of the solenoids 64 or 65 will also receive electrical current, will be magnetized and draw soft iron ring 66, and the shaft 27 therewith, in a right handed or left handed direction and thereby cause the motor to rotate one or the other of the gears 28 or 29 and the rest of the bed mechanism therewith, as has been more fully described hereinbefore. The operation of the motor and the respective solenoid will last 80 as long as the respective button is kept pressed and the electrical circuit closed. Upon the release of the button, its spring contacts will be automatically returned to the open position, the flow of the electrical energy broken, 85 and forked member 67, as well as the shaft 27, returned to their middle position by one of the pins 70 and 71.

The diagram of the electrical connections and circuits necessary to obtain the different movements of the bed and its operating mechanisms, indicated hereinbefore, is shown in Fig. 9. The electrical energy is received from any of the usual outside sources at 72 and will be returned to the same as at 73. The energy is led into the main conductor 74 from which it may be branched off into the different parts of the mechanism, while it is returned through the second main conductor 75 to which the return ends of the different electrical circuits are connected. The motor will receive its circuit from the branching off point 76, the circuit passing through the switch 77, both contact points 78 and 79 of which are adapted to make electrical contacts with an electro-conductive arm 80, arm 80 is secured on the shaft of the oscillating lever 67, described hereinbefore, but insulated therefrom as well as from all other metallic parts of the mechanism. It will be seen that the springs 70^a and 71^a of the pins 70 and 71, described hereinbefore, will tend to keep the arm 80 in a neutral central position, as shown, in which case it does not make contact with either of the points 78 or 79. As soon, however, as one or the other of the solenoids 64 or 65 is energized the arm 80 will be moved upward or downward and will complete the electrical circuit starting from 76, going through the arm 80 and from there through the conductor 81 into 100 105 110 115 120 125 130

the armature 59 of the motor, and returning to the branching off point 82 in the return conduit 75.

Suppose the user of the bed wants to raise the head portion of the same. He then will press the button 45 which will cause the mechanisms to operate in such a manner as to move the head portion of the bed in an upward direction. As will be seen by inspecting Fig. 9, pressing down the button 45 will close the three contact points 45^a, 45^b, and 45^c, and three circuits will be closed thereby, one for magnetizing the respective solenoid, another one for the armature of the motor, and a third one for its magnets. The solenoid circuit will start at 83, pass through the contact point 45^a and downwardly through 84, 85, 86, into the coil of the solenoid 64 and return to the main conduit 75, as at 87. The solenoid 64 will cause the shaft 27 to slide in a left handed direction, as described hereinbefore, connecting its driving gear 26 with the driving gear 29 for the head and feet movements of the bed, and at the same time will close the armature current of the motor at 79. The closing of the contact spring 45^c will start a current from 88 down through said switch, through the points 89 and 90, and 90^a through the magnet coils 61^a in the direction of the arrows 91, and returning through the points 92, 93, 94, and spring contact 45^b into the return conduit 74 as at 95. We may now arrange the coils in the armature and magnets of the motor in such a relation that the above described magnetizing current will cause the worm 33 to lift the head end of the toothed segments 30. The head portions of the bed will thus be raised in a slow, smooth and even manner as long as the button 45 is kept pressed down. As soon as the button is released the spring contacts at 45^a, 45^b, and 45^c will be broken, the solenoid current stopped, shaft 27 returned in its center position and the rotation of the motor, as well as its connection with the rest of the bed mechanism, cut off.

When it is desired to lower the head portions of the bed, the button marked 49 will be pressed and the contacts 49^a, 49^b and 49^c closed. An observation of the different resulting new circuits will reveal the fact that both, solenoid and armature circuits will remain the same as before, which will cause the same portions of the bed mechanisms to be operated, but the magnet circuit will be reversed starting from 88 through 49^b, 92, through the magnet coils 61^a but in a reversed direction as before, following the dotted arrows 96, then through the points 90^a, 90, switch 49^c and into the main return conductor 75, as at 95. The result will naturally be a reversed rotation of the motor and a reversed movement of the respective bed mechanisms so that the head portion of the same will now be lowered instead of

being raised when the button 45 was pressed.

A close observation of the other parts of the electrical diagram will reveal the fact that the pressing of the other buttons, from 46 to 52, will cause the other portions of the bed to be raised or lowered in a similar manner, and that the pressing of one button will close one set of circuits only and will start one kind of movement of the bed only, while all the other circuits will be left open and the bed cannot execute any other movement simultaneously. This will insure that the pressing of a button will start one selected movement only and will prevent any other parts of the electrical and mechanical mechanisms from operating and causing confusion or danger to the occupant of the bed.

After a certain portion of the bed has been raised or lowered by pressing of the appropriate button, and said button released, the bed mechanism will remain in the position reached, on account of the driving worms 33 and 42 being made self-locking.

Thus stop means 103 will be provided upon opposite end portions of each of the segmental racks to co-act with the respective buttons. Suitable link mechanism can be provided between the various levers 102 and the various buttons. Said link mechanism can be readily arranged for this purpose by anyone skilled in the art to cooperate in an effective and reliable manner with a compactly constructed switch box.

Changes and variations may be made in the construction of the parts within the limits of the claim without departing from the spirit and scope of the invention.

One such modification might be in providing two motors for our invention instead of the one shown in the preferred embodiment, one motor being used for each, the head and feet, and the right and left side movements.

Another modification would consist in providing four toothed segments, one for each of the four movable portions of the bed, which would operate in a similar manner as the toothed segments described in the preferred embodiment.

What we claim as new, is:—

1. An adjustable bed comprising right and left side sections and head and foot sections, means hingedly connecting the sections by which they are each adapted to be angularly elevated, a frame having curved cross guides adapted to support said sections and limit the downward movement thereof, crossed segmental racks slidable in said guides and operable to selectively engage a section to raise and lower the same, and controlling means within reach of the patient for operating the racks.

2. An adjustable bed comprising right and left side sections and head and foot sections, means hingedly connecting the sections by

which they are each adapted to be angularly elevated, a frame having hollow curved arms adapted to support said sections and to limit the downward movement thereof, curved racks slideable in said arms and operating in crossed relation, and adapted to selectively engage a bed section to raise and lower the same, and means for operating the racks independently, as described.

10 Signed at Akron, in the county of Summit and State of Ohio, this 26th day of May, A. D. 1925.

SIMON ROTHAUSZKY.
JOHN SCHLER.
